UNITED STATES PATENT OFFICE.

ERNEST LESLIE RANSOME, OF NEW YORK, N. Y.

COUPLING METAL BARS IN REINFORCED CONCRETE.

SPECIFICATION forming part of Letters Patent No. 694,576, dated March 4, 1902.

Application filed July 13, 1901. Serial No. 68,253. (No model.)

To all whom it may concern:

Be it known that I, ERNEST LESLIE RANSOME, a citizen of the United States, residing in the city of New York, State of New York, have invented Improvements in Coupling Metal Bars in Reinforced Concrete; and I hereby declare the following to be a full, clear, and exact description of the same.

My invention relates to the couplings used in connecting together the twisted tension-bars that are embedded in concrete in order to give added tensional strength thereto. It is also applicable to bars that have not been twisted. Hitherto it has been customary to make such coupling by welding, screwing, hooking, or lapping with long laps. The first is expensive, in many situations impracticable, and generally is uncertain in result. The second is also expensive, involving, as it does, upsetting the metal in order to retain the full strength of the bar. Hooking is seldom used in good practice, as it only utilizes a part of the strength of the bar, and lapping involves too great a waste of steel and is uncertain in result in thin walls.

By my invention I lap the bars and slip a loose sleeve over the lap after the bars are in place. The bars and the sleeve are then united together by the concrete or cement grout of the structure, which flows closely about and between the bars and sleeve, entirely embedding them.

The accompanying drawing illustrates my invention, in which—

Figure 1 is a tension-bar about which a loose open sleeve has been slipped. Fig. 2 is a loose open sleeve in position for slipping over the lap of two tension-bars. Fig. 3 is a loose open sleeve in final position about the lap of two tension-bars. Fig. 4 is a loose open sleeve in final position about a vertical lap. Fig. 5 is a close loose sleeve in final position about a vertical lap.

In carrying out my invention I place one of the bars to be coupled in its place on the concrete and slip over one end thereof a loose sleeve, as shown in Fig. 1. The other bar is lapped over the first one, as shown in Fig. 2, and the sleeve is slipped over the lap, as shown in Fig. 3. The whole is then thoroughly embedded in the concrete of the structure. By preference the coupling is embedded in a finer and richer concrete than the balance of the work. By preference, also, the horizontal couplings are made with open

sleeves that will permit of the ready flow of the concrete or grout between them and the bars. Such coupling-sleeves are preferably made of twisted iron wire or rod with open coils. This open sleeve is almost a necessity in horizontal couplings.

In vertical couplings there is not the same necessity for the open sleeve, and a close sleeve can sometimes be used to advantage, in which case I use either a close coiled sleeve, as in Fig. 4, or a tube sleeve, as in Fig. 5. It is generally preferable, however, to have the sleeve open enough to allow of a union between the concrete that is without with that which is within the sleeve.

The following couplings will when embedded in concrete give the full strength of the bars coupled, the bars and the wire or rods of the couplings being rectangular and cold-twisted:

Bars.	Length of lap.	Coil-sleeve of—	Wire coils.
1×1	4"	1 $\frac{1}{2}$	1 $\frac{1}{2}$ " apart.
1 $\frac{1}{2}$ ×1	8"	1 $\frac{1}{2}$	1 $\frac{1}{2}$ " apart.
1 $\frac{1}{2}$ ×1 $\frac{1}{2}$	16"	1 $\frac{1}{2}$	1 $\frac{1}{2}$ " apart.
1 $\frac{1}{2}$ ×2	24"	1 $\frac{1}{2}$	1 $\frac{1}{2}$ " apart.
1 $\frac{1}{2}$ ×2	32"	1 $\frac{1}{2}$	1 $\frac{1}{2}$ " apart.

When plain bars are used, the laps will have to be longer.

By the term "concrete" I include all similar materials that can be poured or handled in a similar manner, such as grout, plaster-of-paris, cast-iron, &c.

Having thus fully described my invention, what I claim, and desire to secure by Letters Patent, is—

1. In reinforced concrete construction a coupling consisting of a lap made by bars and surrounded by a sleeve large enough to slip over the lap; the whole being fastened together by the concrete in which they are embedded.

2. In reinforced concrete construction a coupling consisting of a lap made by bars and surrounded by an open sleeve large enough to slip over the lap; the whole being fastened together by the concrete in which they are embedded.

ERNEST LESLIE RANSOME.
